CLOSURE APPLYING MACHINE

Arthur I. Risser, Chicago, Ill., assignor to U. S.
Bottlers Machinery Company, Chicago, Ill., a
corporation of Illinois

Application December 19, 1938, Serial No. 246,561

3 Claims. (Cl. 226—92)

This invention relates to automatic machines for corking bottles which are continuously passed through the machine, and more particularly pertains to such a machine of the rotary type for handling flanged corks of the type having an enlarged top end adapted to engage over the mouth of a bottle.

Some of the objects of the invention are to provide such a machine that will be simple in construction; that will be compact; that will be capable of operating at a high rate of speed; wherein various operating parts may be quickly adjusted or replaced to enable the machine to handle various sizes of bottles and/or corks; and that will not be liable to get out of order.

Other objects and advantages will become apparent by reference to the specification and the accompanying drawings, in which:

Fig. 1 is a front elevation of the corking machine embodying one form of the invention, with parts broken away, parts in section and other parts being omitted.

Fig. 2 is a detail plan section of the machine, as taken substantially on the section line 2—2 of Fig. 1, with certain parts broken away.

Fig. 3 is a detail bottom plan of parts of the machine as taken substantially on the section line 3—3 of Fig. 1, with parts broken away and parts omitted.

Fig. 4 is a vertical section of the machine, as taken substantially on the section line 4—4 of Fig. 1.

Fig. 5 is a detail section taken on the section line 5—5 of Fig. 4, with parts broken away.

Fig. 6 is a detail plan section taken on the section line 6—6 of Fig. 4.

Fig. 7 is an enlarged detail section taken on the section line 7—7 of Fig. 5.

Fig. 8 is a plan section of the machine, as taken substantially on the section line 8—8 of Fig. 1, with parts broken away.

Fig. 9 is an enlarged sectional detail of a corking head of the machine, as seen in Fig. 4, with certain parts shown in section.

Fig. 10 is a front elevation of the corking head, seen in Fig. 9, as viewed from the section line 10—10 of said Fig. 9.

Fig. 11 is a detail section taken on the section line 11—11 of Fig. 10.

Fig. 12 is an enlarged detail section of a corking head of the machine as taken on the section line 12—12 of Fig. 4, with certain parts seen in elevation.

Fig. 13 is an enlarged detail section taken on the section line 13—13 of Fig. 4.

Fig. 14 is a detail section taken on the section line 14—14 of Fig. 13.

Fig. 15 is a detail section taken on the section line 15—15 of Fig. 13.

Fig. 16 is a detail section taken on the section line 16—16 of Fig. 13.

The machine, as illustrated, includes a supporting frame 1 in the form of a housing having top and bottom walls 2 and 3, respectively, provided with vertically aligned bearings 2a and 3a, respectively, within which is rotatably mounted a hollow shaft 4 extending upward from the housing. Mounted on the shaft 4, to rotate therewith, is a supporting member 5 in the form of a wheel upon which is mounted, for movement to raised and lowered positions, a number of bottle supports 6 equally spaced about the axis of the shaft. The bottle supports 6 comprise shelves having depending shaft portions 7, respectively, reciprocably mounted in bearings 8 of the wheel 5. To prevent the shelves from rotating with respect to the wheel 5, each shelf has a depending pin 9 slidably mounted in a bearing 10 in the wheel.

The shaft 4 is driven to rotate continuously in a clockwise direction, as viewed in plan, and, as the shelves 6 rotate therewith they are moved to raised and lowered positions by a circular cam 11 mounted on the top wall of the housing 1 central with the shaft and causing operation of the shelves through the intermediation of rollers 12 arranged at the bottom ends of the shaft portions 7 of the shelves. The cam 11 is formed to cause the shelves to dwell in their lowered position during rotation thereof within an arc of about 170 degrees while at the front of the machine, and to cause the shelves to be raised when they approach the rear of the machine.

Mounted on the top wall of the housing 1, in spaced relation thereabove, is a hollow table 14 arranged at the front of the machine adjacent the path of the shelves when lowered, with means arranged on the table for feeding filled bottles in position on the shelves to be corked. The bottle feeding means includes an endless horizontal belt 16 in the form of a sprocket chain provided with cleated links. One end of the belt is supported on an idler sprocket wheel 17, and the other end of the belt is supported on a driving sprocket wheel 18 driven by a suitable combination motor and speed reducer 19 through a suitable sprocket and sprocket chain connection 20. The upper stretch of the belt is supported upon the table 14 in the plane of its top surface by being received within a recess or guide- 55

way 21 formed in the table, with the belt being driven so that its upper stretch moves from left to right as seen from the front of the machine.

The bottles to be corked are placed on the belt 5 at the left hand side of the machine, as seen in Fig. 1, where they are directed between suitable guides 22 and 23 into pockets 24 of a star wheel 25 which rotates in a counter-clockwise direction and cooperates with an arcuate portion 26 10 of the guide 23 to direct the bottles onto the shelves successively as the shelves are being carried past the front of the machine. As the shelves are raised at the rear of the machine, the bottles thereon are brought into cooperative 15 relation with corking means of the invention which applies flanged corks to the bottles.

As each shelf reaches its lowered position, after the bottle thereon has been corked, the bottle is received within one of a number of pockets 28 20 of a star wheel 29 which rotates in counter-clockwise direction, as seen in plan, and cooperates with the guides 30 and 31 to direct the bottles onto the belt to be carried thereon from the machine.

25 The star wheels 25 and 29 are secured on upright shafts 32 and 33, respectively, rotatably mounted in suitable bearings in the table 14 and the top wall of the housing 1, with each shaft having a spur gear 34 meshing with a spur gear 35 secured on the hollow shaft 4 for causing the star wheels to rotate in timed relation with the bottle supports or shelves 6.

30 The star wheels and bottle supports are rotated by an electric motor 36 which drives the star wheel shaft 32 through the intermediation of a suitable speed reducer 37. The motor and speed reducer are mounted within the housing 1, with the speed reducer having an upright drive shaft 38 connected with the bottom end of the 35 star wheel shaft 32 through a suitable automatically releasable clutch 39. The clutch is of a common type designed to automatically release in the event the star wheel shaft is prevented from rotating by a bottle becoming jammed in 40 the machine.

45 The bottle corking means will now be described.

50 Mounted on the top end of the hollow shaft 4 is a supporting member 42 in the form of a wheel having a downwardly extended hub 43 surrounding the shaft with a bifurcated lower end clamped to the shaft by bolts 44 passing through adjacent flange portions 45 of the bifurcations 46 of the hub. The hollow shaft 4 is externally 55 threaded, as at 47, to receive the internally threaded sleeve segments 48 secured in the bifurcations 46, respectively, whereby the wheel 42 may be adjusted to elevated or lowered positions on the shaft by loosening the bolts 44 and then 60 turning the wheel on the shaft in the proper direction.

65 Mounted on the supporting wheel 42 and arranged above the shelves 6, respectively, are a number of corking heads A designed to apply the flanged corks to the bottles on the shelves as they are moved to raised position at the rear of the machine. To this end, each corking head includes a cylindrical head 50 mounted on the wheel 42 so as to be central with a bottle positioned on the shelf 6 therebelow. Each head 50 has a reduced bottom portion 51 received within the upper portion of the vertical bore 52 of a bearing formation 53 of the wheel 42 to which the head is secured by bolts 54 passing through a 70 peripheral flange 55 of the head.

In each head 50 is mounted a spring-pressed cork-engaging plunger 56 arranged centrally in the head with a lower enlarged portion 57 reciprocably mounted in the reduced bottom end 51 of the head, and having an upper stem 58 slidably received within the bore of a plug 59 threaded within the upper portion of the head for adjustment axially therein. The plunger 56 is resiliently held in lowered position in the head 50 by the portion 57 of the plunger having a 10 flange 60 spring-pressed against a shoulder 61 in the head by a coiled spring 62 surrounding the plunger stem 58 and being interposed between the said flange and the plug 59 which is adapted for regulating compression of the spring. 15

Each plunger 56 has an enlarged cork-engaging bottom end 63 normally positioned at the bottom end of the bore 52 of the bearing portion 53 of the wheel 42, with means being provided forming a recess directly under said bottom end 20 of the plunger having an inlet opening in the direction of or toward the periphery of the wheel and adapted to receive and position a flanged cork centrally below the plunger in an upright 25 position. The means forming the recesses of the 30 heads includes a pair of segmental or semicircular ring portions 64 secured on the under side of the wheel 42 by bolts 65, with said ring portions having outer or peripheral edges 66 concentric with the wheel and having notches 67 therein disposed under the plungers 56, respectively, and adapted to receive the flange of a cork, such as the type shown in Figs. 9 to 12, with a cork portion 68 adapted to be received within the neck of a 35 bottle, and including an enlarged head or flanged top end 69 adapted to engage over the mouth end of the bottle.

40 Disposed below each notch 67 of the ring segments 64 is a pair of laterally spaced horizontal arms or fingers 70 having free end portions 71 normally positioned to receive the portion 68 of a cork therebetween so that the flange 69 of the cork will be supported thereon as same is received within the notch 67. The fingers 70 are pivoted to the ring segments as at 72 to permit 45 movement of the pairs of fingers from under the flange of a cork as same is being applied to a bottle. Disposed between each pair of fingers is a stop 73 against which the fingers are resiliently held in closed position in supporting relation 50 with the flange of a cork by a coiled tension spring 74 connected between the fingers. The stops 73 comprise the heads of screws threaded within apertures in the ring segments 64.

55 As each corking head approaches the front of the machine, a cork is fed into the recess thereof just prior to the feeding of a bottle onto the shelf 6 therebelow. Then as the bottle is raised by the shelf, the cork is caused to enter the neck of the bottle with the plunger 56 of the corking head serving as a resilient backing for the cork and arranged to be slightly raised against the tension of the spring 62 as the bottle reaches its uppermost position to insure pressure engagement of the flange of the cork with the mouth 65 end of the bottle, as seen in Fig. 12. While the bottle is being raised after it initially engages the cork, the fingers upon which the cork is supported are spread apart from under the flange of the cork by the free ends of the fingers being 70 provided with opposed cam formations 75, or tapered portions, adapted for camming engagement with the mouth end of the bottle. The flanges of the corks are of about the same diameter as the mouth end of the bottles, so that they 75

may pass by the fingers as the bottles to which they are applied are lowered on the shelves to be carried from the machine.

Arranged below the pairs of fingers 70 and mounted on the ring segments 64 are bottle centering members 76 in the form of tubular sections coaxial with the plungers 56 of the corking heads respectively. The bore portion 77 of each centering member is adapted to snugly receive the neck of a bottle, and is of such length as to maintain the bottle central with the plunger thereabove as the bottle is being raised from a position where its neck initially engages the cork. The centering members are secured on the ring segments 64, in spaced relation under the pairs of fingers 70, by bolts 78 passing through lugs 79 formed on opposite sides of the tubular sections, with the bottom ends of the bores of said sections being tapered, as at 80, to guide the bottles therein as they are raised on the shelves.

The cork feeding means of the invention will now be described.

Arranged centrally within the hollow shaft 4 is a stationary supporting shaft 85 having its lower end firmly secured in a bearing 86 in the bottom wall 3 of the housing 1, and having its upper portion supported within a bearing 87 in the top end of the shaft 4. The shaft 85 extends upward beyond the top of the shaft 4, with the supporting wheel 42 having a ball-bearing 88 secured in its hub which is slidably received on the shaft 85 for a purpose later dwelt upon.

Adjustably mounted on the top end portion of the shaft 85 is a supporting member 89 upon which is supported cork feeding means for feeding flanged corks to the corking heads as they approach the front of the machine.

The supporting member 89 is in the form of a sleeve received on the shaft 85. The sleeve has a longitudinal key 90 slidably received in a keyway 91 of the shaft 85 to hold the sleeve from rotating, and a set screw 92 is provided on the sleeve for engagement with the shaft to hold the sleeve in adjusted positions.

The bottom end of the sleeve 89 engages the bearing 88 of the supporting wheel 42 so that when the wheel is adjusted to raise or lower the corking heads in accordance with the height of the bottles to be corked, the sleeve may rest upon or be supported by the wheel so as to be adjusted therewith in maintaining the feeding means in cooperative relation with the corking heads.

The cork feeding means includes a cylindrical hopper disposed at the front of the machine, being adapted to receive a supply of flanged corks and having means associated therewith for directing the corks into the corking heads in proper position. To this end, arranged at the front of the machine is a stationary supporting disc 95 slanting upwardly and inwardly of the machine, with its axis intersecting the axis of the shaft 85, and being secured at its top edge portion to a bracket 96 mounted on the top end of the supporting sleeve 89. The hopper is arranged over the disc 95 and includes an upper cylindrical wall section 97 secured to brackets 98 arranged thereabout and mounted on the periphery of the supporting disc 95. The hopper also includes a rotating lower section including a cylindrical wall portion 99, or ring, registering with the wall portion 97 and being secured on a disc 100 forming the bottom of the hopper and being received within a central depression 101 in the supporting disc 95 so that its upper surface will be in the plane of the upper surface portion 102 of the

disc 95 thereabout. The lower section of the hopper is rotatably supported on the supporting disc 95 by its bottom 100 being secured to the upper end of a shaft 103 rotatably mounted in a bearing 104 secured on the under side of the disc 95.

In the wall portion 99 of the lower section of the hopper is a plurality of cork passageways 105 which are formed to only permit the flanged corks to pass therethrough whose flanged ends face or rest upon the bottom 100 of the hopper, with said wall portion being rotated in a clockwise direction, as viewed in plan, for agitating the corks therein into position for passage through the passageways. To this end, each passageway is T-shaped with its widest portion 106 arranged adjacent the upper surface of the bottom 100 of the hopper and being adapted to receive the flange of a cork. The upper or narrow portion 107 of each passageway is narrower than the diameter of the flange of a cork but is adapted to permit the passage of the portion 68 of the cork therethrough.

As the corks are discharged from the hopper through its passageways, they are brought into cooperative relation with means which directs them in uniform single order into position to be fed into the corking heads. To accomplish this, mounted on the supporting disc 95 concentric therewith is an arcuate guide 108 having a portion 109 spaced from the upwardly moving side of the hopper wall 99 so as to form a channel-way therewith, and with the upper surface 102 of the supporting disc 95, in which the corks are received from the hopper in uniform single order. As the corks move downward in the channel-way by force of gravity, they are directed into the upper end of a magazine 110 arranged to guide the corks into the recesses of the corking heads. To this end, the guide portion 109 of the guide 108 terminates at the lower edge portion of the supporting disc into a downwardly curved end portion 111 alongside of which the corks are guided into the upper end of the magazine by an arcuate guide 112 mounted on the supporting disc 95 opposite the guide portion 111 so as to form therebetween a downward continuation of the channel-way. The guides 108 and 112 are provided with rails 114 and 115, respectively, on their top sides, with each rail arranged to form a guide-way along the side of its respective guide in which the flanges of the corks are received to hold or guide the corks in uniform single order into the magazine.

The passage-ways of the wall portion 99 of the hopper, at the downwardly moving side thereof, are blocked to prevent passage of the corks therethrough until they approach the upwardly moving side of the wall portion by an arcuate guard rail 115a mounted on the supporting disc 95 with its lower end terminating at the guide 112.

The magazine 110 is mounted on the supporting disc 95, and includes a bottom wall 116 and side walls 117 having rails 118 provided thereon, respectively, forming guideways along the inner sides of the side walls in which the flanges of the corks are received to guide the corks in side by side single order. The magazine continues from its top end arcuately downward and inward towards the path of the corking heads, and terminates in a horizontally disposed discharge end 119 arranged to register with the recesses of the heads respectively as they are rotated.

As each corking head is brought into position with its recess in register with the discharge end 119

of the magazine, the end cork in the magazine is forced into the recess by means of an air jet 120 arranged in the side wall of the magazine at an angle to direct air under pressure at the rear of the cork, as best seen in Fig. 11. Air under pressure is supplied to the jet 120 by means of an air-pressure pump 121 driven by an electric motor 122 and being connected with the jet by means of an air conduit 123, as diagrammatically illustrated in Fig. 4.

For regulating the pressure of the air at the jet, a pressure regulator 124 is included in the conduit 123, with the regulator being mounted on the bracket 96 of the supporting sleeve 89. That portion of the conduit 123 between the regulator and the pump 121 may be of flexible material to permit vertical adjustment of the regulator with the supporting sleeve 89.

When the recesses of the corking heads are not in register with the discharge end of the magazine, the corks are held in said end by being engaged by the peripheral edge portions 66 of the ring segments 64, whereby the end cork in the discharge end will snap into the recess of a head as it passes by the magazine.

In accordance with the objects of the invention, a simple operable connection is provided between the corking head supporting wheel 42 and the hopper for rotating the lower section of the hopper. To this end, the supporting wheel 42 has an upwardly projecting hub portion 126 on which is secured a spur gear 127 which meshes with a spur gear 128 arranged on the bottom end of a vertically disposed shaft 129 which is rotatably mounted in a bearing 130 on the supporting sleeve 89, with the gear 128 being in driving connection with the shaft through the intermediation of a suitable friction clutch device 131 mounted on the shaft. The shaft 129 is in driving connection with the shaft 103 of the hopper by having a bevel gear 132 provided on its top end meshing with a similar bevel gear 133 provided on a horizontal shaft 134, with said gear 133 being in mesh with a similar bevel gear 135 secured on the bottom end of the shaft 103. The horizontal shaft 134 is secured in spaced bearings 136 of the sleeve 89 and has its ends received within bearings 137 provided at the ends of arms 138 formed on the bearing 104 of the disc 95. Thus the bearing 104 with its arms 138 serves as a bracket extension of the supporting sleeve to firmly support the cork feeding device.

By virtue of the structure described, a simple corking machine for flanged corks has been provided, that is capable of more positively positioning the corks in cooperative relation with the corking mechanism than machines heretofore constructed; that maintains the corks in such position until after they have been initially applied to the bottles; that includes corking heads and feeding means therefore that may be easily adjusted together to accommodate bottles of various height; that includes a most compact and simple supporting structure for the corking heads and feeding means; and wherein the corks are more positively fed to the corking heads in uniform side by side single order to insure the proper positioning of same in the heads.

Another important feature of the invention is that the notched cork-positioning ring segments

64 with their cork-supporting fingers 70 may be easily removed from under the supporting wheel 42, so that a number of sets of such ring segments with similar fingers may be kept at hand for attachment to the wheel for positioning corks of various sizes.

Having thus described my invention, I claim:

1. In a machine of the class described, a corking device having means for applying to a bottle a cork having a flanged top-end adapted to engage over the mouth-end of the bottle, including a cork applying head provided with means to position the cork in cooperative relation with the applying means and including means operated by the bottle after initial application of the cork therein for releasing the cork from the positioning means, wherein the positioning means includes a member detachably connected with the head and having a notch in an edge thereof adapted to receive and position the flanged end of the cork, and wherein the last means includes a pair of horizontal fingers arranged under the positioning member to engage under the flange of the cork at opposite sides thereof, said fingers being pivoted to the member for horizontal movement out from under the flange, and said fingers having cam formations respectively formed for camming engagement with the bottle after insertion of the cork therein to cause said movement of the fingers.

2. In a machine of the class described, a number of corking devices arranged about and mounted to rotate around a vertical axis, each device having means for applying to a bottle a cork having a flanged top-end adapted to engage over the mouth-end of the bottle upon rotation of the device about said axis, including means to position the cork above the bottle prior to the applying operation and being inclusive of means operated by the bottle after initial application of the cork therein for releasing the cork from the positioning means, wherein the positioning means comprises a member detachably connected with the devices to rotate therewith and having an edge of circular form concentric with the axis provided with notches therein arranged and adapted to receive and position the flanges of the corks in cooperative relation with the devices respectively, and wherein the last means comprises pairs of horizontal fingers arranged to engage under the flanges of the corks respectively at opposite sides thereof and being pivoted to the member for movement out from under the flanges.

3. In a machine of the class described, a corking head for corks having a flanged top end adapted to engage over the mouth end of a bottle, including means forming a recess adapted to receive and position the flange of the cork comprising a spring-pressed plunger having a bottom end forming the top wall of the recess, a member arranged below the plunger and having a notch in an edge thereof adapted to snugly receive the flange of the cork, and a pair of spring-pressed fingers normally arranged to engage under the flange of the cork at opposite sides thereof to support same in the notch and being capable of movement out from under the flange to permit removal of the cork from the recess.
